UNITED STATES PATENT OFFICE

CLIFTON W. NIXON, OF NEW YORK, N. Y.

VENDING APPARATUS

Application filed June 7, 1926. Serial No. 114,113.

My present invention relates to vending apparatus, the invention being more particularly related to coin-controlled delivery apparatus for use in vending machines where-
5 by packaged goods may be dispensed.

A main object of my invention is to simplify and improve the general construction, arrangement and operation of apparatus of this character.

10 Another object is the provision of vending apparatus of this character which will embody certain desired features of simplicity, efficiency and convenience, and which will be economical in manufacture and durable in
15 use.

Another feature of my invention has reference to the provision of a single unit involving an arrangement of operating means, coin-controlled mechanism and delivery ap-
20 paratus, which single unit will be capable as an entity device, of being readily installed in and as readily removed from any suitable vending machine.

A still further object of my invention is the
25 provision of a vending apparatus for use in machines where bulky goods, such as boxes of candy, packaged sandwiches, pies, cakes and the like, are dispensed.

With the foregoing objects in view and
30 others, my invention resides in the peculiar construction, arrangement and combination of parts hereinafter described and more particularly pointed out in the annexed claims, reference being had to the accompanying
35 drawings, in which:

Fig. 1 represents a sectional elevation from front to rear through a machine embodying my improved vending apparatus, the machine being fragmentally shown;

40 Fig. 2 is a rear elevational view and section of my vending apparatus in association with a fragmental portion of the machine, which portion is shown in cross-section, this view illustrating in particular the arrangement of the delivery frames and merchandise stacks;

45 Fig. 3 represents a top plan view of my vending apparatus detached from the machine;

50 Fig. 4 is a side elevational view of my

vending apparatus, parts being shown in section and parts being broken away;

Fig. 5 is a cross-section on an enlarged scale, taken on the line 5—5 of Fig. 3; and

Fig. 6 is an enlarged section taken on the line 6—6 of Fig. 4.

My improved vending apparatus, in its preferred form of construction as illustrated in the accompanying drawings, comprises a supporting frame 7 including a base 8 having a front upright 9 and a rear upright 10. This frame is preferably cast and carries all of the parts of the apparatus.

11 designates an operating shaft which is mounted for reciprocating and turning movements in the front upright 9 and upon a stud shaft 12 secured to and projecting forwardly from the rear upright 10, the shaft 11 for this purpose being provided with a central bore 13 in which the stud shaft 12 is received. The operating shaft 11, intermediate its length, is made with a reduced portion 14 to provide spaced-apart shoulders 15 and 16.

17 designates a coin slide which is vertically positioned to slide upon the base 8 in a groove or slideway provided by the guide members 18 and 19 secured upon the base 8. At its top end, the coin slide 17 is formed with curved flanges 20 and 20' which embrace the reduced portion 14 of the shaft between the shoulders 15 and 16 thereon. By this arrangement, the coin slide is reciprocated with the operating shaft, while the last-mentioned is capable of being turned independently of the coin slide. At its front end, the coin slide

80 is made with a coin head 21 slotted at 21' to receive the edge of a coin. Arranged to have pivoting movement upon a pin 22 projecting from the coin slide is a latch member 23 which cooperates with the coin

85 slide and the head 21 thereon to form a coin-seat for a coin as 24, the latch member being suitably recessed at 25 to receive the edge of the coin and to sustain the same in conjunction with the head 21. Said latch member 23 is provided with a tooth 26 at its rear end. In the present embodiment the guide 19 serves as a keeper for the latch member, the same being provided with a notch 27 fashioned to receive the tooth 26. Just back

of the notch 27, the guide 19 is also made with a cam-like landing 28 with which the tooth 26 cooperates so as to hold the latch 23 in position for the coin to enter its coin-seat when it falls through the transverse coin slot 29 provided in the operating shaft 11. A spring 30, having its forward end arranged on a stud 31 on the head 21, having bearing on the pin 22 and having its rear end attached to a cross piece 32, serves as means for constantly urging the latch member downwardly into position for the engagement of the tooth 26 with the notch 27. As clearly shown in the drawings, the cross piece 32 extends from the opposite faces of the latch member and works in a suitable slot 33 provided in the coin slide. When under this arrangement, a coin is lodged in the coin-seat formed between the coin slide and the latch member, the operating shaft can be pulled outwardly since the lodged coin holds the latch member in elevated position so that the tooth 26 cannot enter the notch 27. When, on the other hand, there is no coin in the coin-seat, the operating shaft cannot be pulled outwardly since upon the initial movement thereof the tooth 26 will slide into the notch 27. The cross piece 32 serves as means through which to elevate the latch member for the release of the lodged coin at the proper time as will hereinafter more fully appear.

Clamped upon the rear end of the operating shaft is a T-shaped member 34 which I will refer to as a key head. Being clamped tightly to the operating shaft, this key head moves with both the reciprocating and turning movements of said shaft. 35 and 36 designate fixed rods which are supported by and connect the front and rear uprights 9 and 10 just above the base 8. Slidable upon each of these fixed rods is a delivery frame 37 composed of a back part 38 carrying two outwardly projecting parts 39 each terminating in an upwardly projecting flange 40. From an inspection of the drawings, it will be seen that each of these U-shaped delivery frames 37 is slidably mounted by passing the supporting shaft through the outwardly projecting parts 39 at points near the back part 38. Each delivery frame is mounted not only for reciprocation with the operating shaft but also for independent vertical movement, and it is held substantially in horizontal position by means of a spring 41 which is applied to the back part 38 so as to have bearing upon the top edge of the base 8. Now, the key head 34 is designed to be employed as the means by which either one of the delivery frames 37 may be reciprocated with the operating shaft 11. To this end, the back part 38 of each delivery frame is provided with a notch 42 for the reception of the curved edge 43 of the key head.

65 In the present embodiment, means is pro-

vided whereby to prevent the outward movement of the operating shaft except when the key head is interengaged with one of the delivery frames. This means comprises an abutment 45 located in proper position below the operating shaft and between the rear parts 38 of the delivery frames. Said abutment is supported upon posts 46 and 47 which rise from the base. This abutment terminates at the rear just short of the turning position of the key head when the operating shaft is at its rear terminal of movement and in position for advancing or outward movement. Should an effort be made to advance or pull out the operating shaft when the key head is not engaged with one of the delivery frames, the terminal 48 of the key head will engage on the end of the abutment. So also, should an attempt be made to turn the operating shaft during its advancing or retiring movements, the abutment 45 will be in the way of the terminal 48 of the key head. Under this arrangement, it will be seen that the operating shaft can be turned only when it is at its rear terminal of movement, the position from which the advancing or pull-out stroke is effected and the position where the key-head is clear of the abutment.

The operating shaft 11, as hereinbefore intimated is a pull shaft; and to this end it protrudes a distance in advance of the front upright 9 where it is provided with a knurled knob 49 adapted to be grasped by the fingers. Said operating shaft 11 as well as the two delivery frames 37 is automatically repositioned after each advancing or pull-out movement by means of a spring 50 which is loosely coiled intermediate its ends about the post 47 between the base and the abutment. One extremity 51 of this spring extends obliquely across the rear part 38 of one frame and is attached to a link 52 whose forward end is pivotally mounted on a post 53 carried by the rear part 38. The other extremity 54 of the spring similarly extends obliquely across the back part of the opposite frame and connects with the link 52 attached to the post 53 of that frame. By this arrangement, either one of the delivery frames may be drawn forwardly in conjunction with the delivery shaft without affecting the other of the delivery frames. When the operating shaft has been pulled out and released, the spring 50 operates to reposition the particular delivery frame which accompanies the operating shaft and also the operating shaft itself because of the interconnected key head.

In Figs. 1 and 2, my vending apparatus is illustrated by way of example in connection with a suitable vending machine 55. Here it will be noted that the supporting frame 7 is secured in the upper part of the main body 56 of the machine and extends from the front wall 57 to the rear wall 58 thereof. Rising upwardly from the main body 56 of the ma-

chine at the rear thereof are two compartments 59 and 60 provided with partial bottoms 59' and 60' respectively. These compartments are constructed to hold in stacked arrangement the goods which are to be sold. 5 The goods may comprise packaged sandwiches, packaged pies, cakes or other pastry, boxes of candy or other packaged goods capable of being sold by a machine of this type. 10 Each of the partial bottoms 59' and 60' is provided with an opening 61 which extends from the front to the rear. As illustrated in Figs. 1 and 2, the vending apparatus is located so that the delivery frames 37 come just below the partial bottoms so that the flanges 40 of the rear projecting parts 39 can be advanced and retired through the openings 61. When the machine is set for operation, the flanges 40 of the rear projecting parts 39 extend upwardly behind the lowermost packages 62 in the compartments 59 and 60; while the flanges 40 of the front projecting parts 39 extend upwardly in front of said lowermost packages 62. The bottoms 59' and 60' of 25 the compartments, being partial and of less dimension than the back parts 38 of the delivery frames, the front flanges 40 are spaced a distance in advance of said partial bottoms as indicated in Fig. 1. When the operating 30 shaft is pulled out, the delivery frame, which is keyed therewith by the key-head, detaches and pulls forward the lowermost package so that it will drop down of its own weight upon the slideway 63 for delivery to the cup 64 where it may be obtained by the purchaser. 35 Upon the release of the lowermost package, the entire column of packages settles down so that the next succeeding package 65 falls upon the flange 40 of the rear projecting part 39. The impact upon the flange 40 causes the delivery frame to sink down until the weight of the column of packages rests upon the partial bottom so that the retiring movement of the delivery frame may take place to engage the flange 40 behind the package 62 which is now the lowermost package of the column. 40

As the delivery frame sinks under the impact of the falling column of packages a pin 50 66, which projects from the rear part 38 moves upwardly and engages the cross piece 32 so that the latch 23 is elevated to release the lodged coin 24 which thereupon falls through suitable slots 67 and 67' in the guide 55 19 and in the base, respectively, for deposit in the cash box 68.

In practice the shaft 49 is provided with a suitable index (not shown) adapted to cooperate with a dial indicating the goods contained in compartments 59 and 60. The customer, therefore, first dials the goods he desires to purchase and this operation engages the key-head with the delivery frame corresponding to the column of goods dialed. 60 Thereupon the customer deposits his coin in

the deposit chute 69. The deposited coin falls through the coin slot 29 of the shaft and is lodged in the coin-seat thereby holding up the latch against the resistance of spring 30 so that the tooth 26 cannot engage the notch 27. Upon depositing his coin the customer pulls out the operating shaft and releases the same. This operation effects the delivery of a package of goods and releases the deposited coin for its passage to the cash box. 70 75 When no coin is deposited in the chute 69, the shaft cannot be drawn out since upon the initial movement of the shaft the tooth 26 slides into the notch 27 thereby preventing any further movement. Upon the release of the knob after the initial movement, the spring 30 repositions the parts so that the tooth 26 slides upwardly to rest upon the cam-like landing 28 for the next operation. 80

While I have illustrated and described the preferred form of construction for carrying my objects into effect, this is capable of variation and modification without departure from the spirit of the invention. I, therefore, do not wish to be limited to the details of construction herein set forth, but desire to avail myself of such variations and modifications as come within the scope of the appended claims. 85

Having thus described my invention, what I claim and desire to secure by Letters Patent is:

1. In vending apparatus provided with mechanism for controlling advancing movement of operating means comprising a shaft mounted for advancing and retiring movement and also for turning movement, a tiltable delivery frame mounted for advancing and retiring movement; and a key-head on said shaft arranged to be swung into engagement with said frame to advance and retire said frame with said shaft said frame being tilttable independently of its movement with said shaft, substantially as described. 100

2. In vending apparatus provided with mechanism for controlling the advancing movement of operating means comprising a shaft mounted for advancing and retiring movement and also for turning movement, a tiltable delivery frame mounted for advancing and retiring movement; means under the control of the turning movement of said shaft for connecting said shaft and frame whereby to advance and retire them together; said frame being tilttable independently of its movement with said shaft; and means for automatically retiring said shaft and frame after each advancing operation, substantially as described. 115

3. In vending apparatus provided with mechanism constituting a locking device, the combination with a movable shaft arranged to be operated when said locking device is in an unlocked state, a fixed shaft; a tiltable delivery frame movably arranged on said fixed 120 125 130

shaft; and means for establishing a connection between said movable shaft and said delivery frame for moving the latter with the former, said frame being tiltable on said fixed shaft independently of its movement with said movable shaft, substantially as described.

4. In vending apparatus provided with mechanism constituting a locking device, the combination with an operating shaft associated with said locking device to have turning movement and also to have longitudinal movement when said locking device is in an unlocked state, two fixed shafts; a tiltable delivery frame slidably mounted on each of the fixed shafts; and a key-head on said operating shaft adapted to be engaged with either of said delivery frames whereby to move the engaged delivery frame with the longitudinal movement of said operating shaft, said delivery frames being tiltable independently of each other and independently of their movement with said operating shaft, substantially as described.

5. In vending apparatus, a supporting frame; a movable operating shaft and a fixed shaft carried thereby; a delivery frame forming an open pocket mounted near one end to slide and swing on said fixed shaft; resilient means for positioning said delivery frame; and means on the operating shaft for establishing an operative connection with said delivery frame, substantially as described.

6. In vending apparatus, a supporting frame; a pull-shaft and a fixed shaft carried thereby; a delivery frame forming an open pocket mounted near one end to slide and swing on said fixed frame; resilient means for positioning said delivery frame; means on the pull-shaft for establishing an operative connection with said delivery frame; and means for repositioning said delivery frame and pull-shaft after each operation, substantially as described.

7. In vending apparatus, a supporting frame; a rotary pull-shaft and a fixed shaft carried thereby; a delivery frame, which forms an open pocket for goods to fall therethrough, mounted near one end to slide and swing on said fixed shaft and notched; and a key-head on said pull-shaft adapted to be received in said notch whereby to move said delivery frame with said pull-shaft and to permit relative swinging movement of said delivery frame, substantially as described.

8. In vending apparatus, a supporting frame; a rotary operating shaft arranged on said frame and slideable from terminal position; a fixed shaft on said frame; a delivery frame, which forms an open pocket for goods to fall therethrough, mounted near one end to slide and swing on said fixed shaft and notched; a key-head on the operating shaft adapted to be received in said notch; and an abutment for said key-head to prevent the rotation of the operating shaft except at its

terminal position, substantially as described.

9. In vending apparatus, a rotary shaft and two swingable delivery frames, said shaft and each of said frames being arranged for movement from terminal position; a key-head on said shaft adapted to be keyed with either one of said frames; and means for preventing the movement of said shaft from terminal position except when said key-head is keyed with one of said frames, substantially as described.

10. In combination, a supporting frame, two fixed shafts on said frame; a rotary shaft having reciprocating movement on said frame; a delivery frame slideable on each of the fixed shafts; a key-head on the rotary shaft adapted to be keyed with either one of said delivery frames; a post; a spring coiled intermediate its length about said post and having one extremity connected with one delivery frame and the other extremity connected with the other of the delivery frames, substantially as described.

In testimony whereof, I have signed my name to this specification.

CLIFTON W. NIXON.
